UNITED STATES PATENT OFFICE.

HERMANN NIKODEM, OF HAMBURG, GERMANY.

FOLDING REST FOR FIREARMS.

1,076,692.

Specification of Letters Patent.

Patented Oct. 28, 1913.

Application filed April 9, 1913. Serial No. 759,906.

To all whom it may concern:

Be it known that I, HERMANN NIKODEM, subject of the Emperor of Germany, residing at Hamburg, Germany, have invented 5 new and useful Improvements in Folding Rests for Firearms, of which the following is a specification.

This invention relates to a folding rest for firearms and consists in providing heads 10 on the upper ends of the supporting legs which are adapted to pivot about an axis in a casing, said heads automatically splaying apart the supporting legs, by means of guides provided on the casing, when the legs 15 are swung into position for use, while other guides automatically cause the legs to be brought close together when the support is folded.

Referring to the accompanying drawings 20 which illustrate one form of rest made in accordance with this invention, Figure 1 is a side elevation of the rest shown folded up; Fig. 2 is a corresponding front elevation; Fig. 3 a view of the interior of the empty 25 case showing the guides and a cotter; Fig. 4 is a detail view partly in section showing the positions occupied by the heads of the legs when the legs are opened; Fig. 5 is a side elevation of one of the heads attached to the 30 supporting legs; Fig. 6 is a detail view partly in section showing the positions occupied by the heads of the legs when the legs are closed.

Spring clips *b*, for holding the stock of 35 the gun, are provided on the casing *a*. The legs *d*, provided with feet *c*, are adapted to

pivot, by means of their heads *e*, about a pin *f*, and are adapted to be turned by the tension springs *g* when the detent *i* is disengaged from the notch *n* in the head *e* by 40 pressing on the finger lever *h*. The legs thereupon turn through an angle of 90° and at the same time are splayed apart owing to the upper ends of the heads *e* being pressed together by the guide checks *k* provided in the casing *a* (Fig. 6). The legs 45 can be locked in this position by inserting the cotter *l* in the aperture *m*. To fold up the support, the cotter *l*, being taken out of the aperture *m*, the legs are turned around 50 until the detent *i* reengages in the notch *n* of the head *e*. At the same time the legs are brought together automatically by means of guide strips *o* arranged laterally 55 inside the casing *a* (Fig. 6).

Claim:

In a folding rest for firearms, in combination, a casing, legs pivotally supported thereby, means within said casing to engage the ends of said legs and force them to 60 come together when they are moved into their inoperative positions and means within said casing to engage said legs to force them apart when they are moved into their operative positions.

In testimony whereof I have signed my name to this specification in the presence of two subscribing witnesses.

HERMANN NIKODEM.

Witnesses:

GEORG JOSEF TAIT,
ALFRED JOSEPH.
